UNITED STATES PATENT OFFICE

2,372,082

COILING MACHINE FOR FINE WIRE

Fred B. Iden, Cleveland Heights, Ohio, assignor
to General Electric Company, a corporation of
New York

Application May 5, 1941, Serial No. 391,882

13 Claims. (Cl. 140—71.5)

My invention relates to methods and apparatus for making filaments and other types of resistance elements, such as electrodes, for incandescent and discharge lamps as well as other similar devices. More particularly, my invention relates to a method and apparatus for coiling and otherwise shaping such filaments or resistance elements.

It is desired that such filaments have certain definite shapes in order to reduce the complexity and increase the performance and life of the electrical devices in which they are used. It has not heretofore been possible to manufacture certain preferred forms of filaments so cheaply and readily as to make them available for the less expensive electric lamps and similar devices. An object of my present invention is to provide a method and automatic apparatus for producing such elements cheaply on a commercial scale. Another object of my invention is to provide automatic apparatus for making resistance elements, particularly filaments, having a coiled mid-portion and specifically shaped end or leg portions. Another object of my invention is to provide apparatus for reshaping the end or leg portions of a filament. Other objects and advantages of my invention will appear from the following detailed description and from the drawing.

In the drawing, Fig. 1 is a side elevation of apparatus comprising my invention with a transfer mechanism in the process of carrying a filament from the coiling apparatus to the leg shaping mechanism; Fig. 2 is a horizontal section through the coiling apparatus; Fig. 3 is a side elevation of the leg shaping mechanism at 90 degrees to that of Fig. 1 and with one portion broken therefrom along the line 3—3 of Fig. 1; Figs. 4 and 5 are corresponding side elevations on a larger scale of the central portion thereof showing the filament at the start and finish of the shaping operation; and Figs. 6 and 7 are side and end views of the completely shaped filament on still a larger scale.

My method is characterized by the manufacture of single filaments in successive periods of operation and, in the instance shown in the drawing, has to do with the coiling of the filament at A (Fig. 1) and a second shaping operation at B. The coiling operation, in particular, is preferably performed by apparatus of the general type disclosed in the Illingworth Patent 1,771,927, although it is preferred that the specific apparatus correspond to that disclosed in Iden Patent 2,179,296 in that such apparatus performs the

coiling operation without leaving a mandrel within the coils and is completely automatic and particularly well adapted to operate with the present apparatus comprising my invention. The essential parts of said coiling apparatus, which are shown midway through their cycle of operation in Fig. 2, start each cycle of operation with a movement of the coiling head 10 toward the mandrel 11 and spindle 12. At this time, the mandrel 11 extends from the spindle 12 as shown and a short end of the filament wire 13 extends from the coiling head 10. The shoe 14 on the end of the jaw 15 is also separated from the spindle 12 at this time so that the forward movement of the coiling head 10 can continue until the end of said filament wire 13 is located over the shoulder 16 of the spindle 12. During the movement, the mandrel 11 passes into the opening 17 of the coiling head 10, which is parallel to that containing the filament wire 13. The shoe 14 and jaw 15 are then moved so that the end of the filament wire 13 is clamped to the shoulder 16 whereupon the spindle 12 is rotated about the axis of the mandrel 11 and coiling head 10 is drawn away from the spindle 12 at a very definite rate to cause the filament wire 13 to be wound around said mandrel 11 at a desired pitch. The coiling operation is complete when the correct number of turns have been made to form the coils of the center section 18 of a filament although the axial movement of the coiling head 10 continues until it takes the position shown in Fig. 2 before it stops.

At this time, the center coiled portion 18 of a filament is wound around the mandrel 11 and the opposite end or leg portions 19 and 20 extend in opposite directions therefrom. The end or leg portion 20 of the filament wire 13 between the coils 18 and the coiling head 10 differs from that at the opposite end of the coils 18 in that it is double said leg or end portion 20 and in the next operation is cut in two by movement of the knives 21 and 22. This operation establishes the length of the filament 23 which is comprised of a coiled portion 18 and the end or leg portions 19 and 20 of equal length and allows an end section 20" of the filament wire 13 to extend beyond the coiling head 10 having a length corresponding to one of the end or leg portions of said filament 23. The end section 20" forms the forward leg 19 of the filament manufactured during the next succeeding cycle of operation.

The next step in the cycle of operations overlaps the last step in that the stationary and mov-

able jaws 24 and 25 of the transfer mechanism engage and prepare to grip the coiled portion 18 of the filament 23 before it is stripped from the mandrel 11. The transfer mechanism corresponds closely to the mechanism disclosed in Illingworth Patent 1,733,882 assigned to the present assignee, and comprises a stationary jaw 24 attached to the arm 26 and a movable jaw 25 slidable in ways in the stationary jaw 24. At the moment the jaws 24 and 25 are carried to A, the roller 27 on the end of the lever 28 is in engagement with a "high" part of cam 29, and said lever 28, which is connected to jaw 25 through link 30, holds said jaw 25 in the open position. The lever 28 is pivoted on the screw 31 held by arm 26 and, being under the influence of the spring 32, is turned about said screw 31 in accordance with the changes in shape of the cam 29. When the transfer mechanism is at its limit of movement, the arm 26 engages the stationary stop screw 33 in the adjacent portion 34 of the apparatus and the coiled portion 18 of the filament 23 is within a V notch in the stationary jaw 24. During this latter interval the jaw 15 on the spindle 12 is moved sideward so that the end or leg portion 19 of the filament 23 is released and the mandrel 11 is drawn into the spindle 12 so that the filament 23 is stripped therefrom. The stripping operation is possible only because the coils 18 have unwound a fraction of a turn due to the release of the end or leg portion 20' in the last period of operation. The next operation follows immediately and consists in a movement of the jaw 25 which causes it to engage and grip the filament 23. The jaw 25 is actuated by the rotative movement of the cam 29 which carries a "low" portion thereof below the roller 27 and occurs so rapidly after the mandrel 11 is withdrawn that the filament 23 does not turn or twist from its known position.

The following transferring operation is the result of a swinging movement of the arm 26 which carries it against the stop screw 35 and carries the filament 23 into the shaping mechanism at B. The transferring operation arranges the filament 23 at a definite relation to the die block 36 as indicated in Fig. 1 and as shown in detail in Fig. 4 and is particularly important since it controls the form into which the end or leg portions 19 and 20' are bent by said shaping mechanism. The width of the jaws 24 and 25 is such that they pass between the parts of the shaping mechanism as shown in Fig. 4.

The next operations are those of the shaping mechanism and are brought about while said filament 23 is still tightly gripped by the transfer mechanism. The transfer mechanism now functions as a holder for the filament while the shaping operation is being carried on since the jaws 24 and 25 form the coiled portion 18 thereof into a rigid mass which does not allow the end or leg portions 19 and 20' to move out of position during said operation. This method of operation is preferred because the filament 23 tends to turn out of position since it has, prior to the time it was gripped by the transfer mechanism, uncoiled a portion of a turn and the end or leg portions 19 and 20' are no longer in the same plane.

When the transferring operation has been completed, the fingers 37 and 38 are moved down so as to clamp a short section of the leg portions 19 and 20' next to the coiled portion 18 to the arms 38'-38" of the die block 36. The upper ends of said arms 38'-38" constitute separated supports for the filament ends. The fingers 37

and 38 are in reality separate slides within ways formed by the standard 39, the cover plate 40 and the slide blocks 41 and 42 (Fig. 3) and are moved by the expansion of springs 43 (partly enclosed in a well in each finger) when the pin 44 moves downward. The springs 43 butt against the cap plate 45 attached to standard 39, whereas the pin 44 is carried by a slide 46 in ways in the back of the standard 39 and extends through a slot in said standard 39 to adjacent slots in the back of the fingers 37 and 38. A U-shaped spring 47 in corresponding slots in the front face of the fingers 37 and 38 absorbs all lateral freedom of movement thereof so that they retain very definite positions at all times.

The downward movement of the fingers 37 and 38 is matched by a corresponding movement of the movable dies 47 and 48 located adjacent thereto which movement is continued until the dies have wiped the legs of said filament 23 down about the shaped sides of the die block 36 as shown in Figs. 3 and 5.

The movable dies 47 and 48 are partially located within slots in the slide blocks 41 and 42 respectively and are carried downward by the corresponding movement of said slide blocks 41 and 42 and slide 46 which are interconnected by the pins 49. Slots 50 in the standard 39 give the pins 49 freedom of movement whereas pins 51 attached to slide blocks 41 and 42 provide a positive means of attaching the movable dies 47 and 48 and the slide blocks 41 and 42 together. Springs 52, which are located between the slide blocks 41 and 42 and an extending arm of the movable dies 47 and 48, keep said dies 47 and 48 against the fingers 37 and 38 and the legs 19 and 20' of the filament 23 during most of the period of travel thereof but at the end of said travel the oblique end surfaces 53 of said dies 47 and 48 engage the ends of screws 54 and 55 and are forced inward. This latter movement of the dies 47 and 48 forces the legs 19 and 20' of the filament 23 tightly against the die block 36 and completes the shaping operation.

The movable dies 47 and 48 and the fingers 37 and 38 are now returned to their former position in order that the filament 23 can be removed from the shaping mechanism. The return movements of the apparatus are in reverse order to the other movements thereof and are caused by an upward movement of the slide 46. The slide 46 is located in ways in the back of the standard 39 in which it is held by the plate 56 and is connected through yoke 57 and rod 58 to cam actuated means (not shown) connected to the coiling apparatus and transfer mechanism in order that it and the shaping mechanism will be operated at proper intervals.

The filament 23 is released from the transfer mechanism prior to being taken from the shaping mechanism by a rotative movement of the cam 29 which is turned so that the movable transfer jaw 25 is moved back. The return sweep of the arm 26 has the dual function of carrying the transfer jaws 24 and 25 over into engagement with the filament being formed in the coiling apparatus and of pushing the filament 23 from the shaping mechanism so that it falls into the chute 59 and is carried away from the apparatus.

At this time, the filament 23 (shown in Figs. 6 and 7) is comprised of a coiled mid-portion 18, relatively short leg portions 60 lying very generally in a plane parallel to the axis of the coiled portion 18, and longer leg portions 61 offset from opposite sides of the coiled mid-portion 18 and

both parallel to each other and at right angles to the axis of the coiled portion. The resiliency of the filament has caused the longer leg portions to spring back to the above position although they were bent to the more oblique faces of the die block 36. The very ends 62 of the filament legs 19 and 20' retain the greater portion of the bend which they have received, however, and are located at still another position.

What I claim as new and desire to secure by Letters Patent of the United States is:

1. Apparatus for forming filamentary resistance elements for electrical devices from a wire comprising a mandrel, means for coiling a portion of the wire about the mandrel with a free end portion extending outward substantially parallel to the axis of the coil, means for stripping the coiled portion of the wire from said mandrel, means for gripping the wire at its coiled portion and transferring it to another location and means at said location for bending the uncoiled end portion of said wire so that it extends laterally of the axis of the coil in a definite predetermined direction, said gripping and transferring means being constructed and arranged to hold the filament in definite predetermined relation to said means for bending the wire.

2. Apparatus for forming filamentary resistance elements for electrical devices from a wire comprising a mandrel, means for coiling a portion of the wire about the mandrel with free end portions extending outward substantially parallel to the axis of the coil, means for stripping the coiled portion of the wire from said mandrel, means located adjacent the coiling apparatus for bending the end portions of the wire so that they extend laterally of the axis of the coil in a definite predetermined direction and means gripping the coiled portion of the wire for transferring it to the last-mentioned means and holding it in a definite predetermined position during the said bending operation.

3. Apparatus for forming filamentary resistance elements for electrical devices from a wire comprising means for coiling an intermediate portion of the wire, a die adapted to engage sections of both uncoiled portions of said wire extending beyond the coiled portion, fingers adapted to clamp said sections of the wire against the die, movable dies adapted to bend the free portions of said uncoiled end portions of the wire into engagement with the first-mentioned die to shape them and means for actuating the fingers and movable dies at proper intervals.

4. Apparatus for forming filamentary resistance elements for electrical devices from a wire comprising means for coiling an intermediate portion of the wire, a die adapted to engage sections of both uncoiled portions of said wire extending beyond the coiled portion, fingers adapted to clamp said sections of the wire against the die, movable dies adapted to bend the free portions of said uncoiled end portions of the wire into engagement with the first-mentioned die to shape them, springs urging the fingers toward the said first-mentioned die and the wire, means controlling the movement of said fingers for carrying the movable dies against said wire to bend the end portions over the said first-mentioned die, and separate means for forcing the movable dies toward said first-mentioned die to bend said end portions tightly thereagainst.

5. Apparatus for forming filamentary resistance elements for electrical devices from a wire comprising means for coiling an intermediate

portion of the wire, means located adjacent the coiling means for shaping the wire comprising a die adapted to engage sections of both uncoiled portions of said wire extending beyond the coiled portion, fingers adapted to clamp said sections of the wire against the die, movable dies adapted to bend the free portions of said uncoiled end portions of the wire into engagement with the first-mentioned die to shape them and means for actuating the fingers and movable dies at proper intervals, and means gripping the coiled portion of the wire for transferring it to the last-mentioned means and holding it in position during the said bending operation.

6. In a device of the character described for reshaping the ends of a filament coil having straight end portions extending outward from opposite ends of the coil substantially parallel to the axis of the coil, a die member having sides sloping obliquely inward and downward from its upper edges, means for holding the filament on said die with its said end portions extending across the said edges of the die and laterally outward beyond its said sides, and movable die members on opposite sides of said first-mentioned die member arranged to bend said filament end portions down around the said edges of said first-mentioned die member and then against its said sloping sides.

7. In a device of the character described for reshaping the ends of a filament coil having straight end portions extending outward from opposite ends of the coil substantially parallel to the axis of the coil, a die member having sides sloping obliquely inward and downward from its upper edges, means for holding the filament on said die with its said end portions extending across the said edges of the die and laterally outward beyond its said sides, means for clamping the filament end portions against said die member adjacent its said upper edges, and movable die members on opposite sides of said first-mentioned die member arranged to bend said filament end portions down around the said edges of said first-mentioned die member and then against its said sloping sides.

8. In a device of the character described for reshaping the ends of a filament coil having straight end portions extending outward from opposite ends of the coil substantially parallel to the axis of the coil, a die member having sides sloping obliquely inward and downward from its upper edges, means for holding the filament on said die with its said end portions extending across the said edges of the die and laterally outward beyond its said sides, a pair of clamping fingers mounted above said die member, movable die members mounted above said first-mentioned die member on opposite sides of said clamping fingers, and means for moving said clamping fingers and movable die members downward to first cause said fingers to clamp parts of the end portions of the filament against said first-mentioned die member adjacent its said upper edges and to then cause said movable die members to bend the free end portions of said filament down around the said edges of said first-mentioned die member, and means for then causing said movable die members to move inwardly to press the said filament end portions against the sloping sides of said first-mentioned die member.

9. In a device of the character described for reshaping the ends of a filament coil having straight end portions extending outward from

opposite ends of the coil substantially parallel to the axis of the coil, a die member having sides sloping obliquely inward and downward from its upper edges, means for holding the filament on said die with its said end portions extending across the said edges of the die and laterally outward beyond its said sides, a pair of independently movable clamping fingers mounted above said die member, movable die members mounted above said first-mentioned die member on opposite sides of said clamping fingers, and means for moving said clamping fingers and movable die members downward to first cause each of said fingers to clamp a part of an end portion of the filament with a definite pressure against said first-mentioned die adjacent one of its said upper edges and to then cause said movable die members to bend the free end portions of said filament down around the said edges of said first-mentioned die member, and means for then causing said movable die members to move inwardly to press the said filament end portions against the sloping sides of said first-mentioned die member.

10. In a device of the character described for reshaping the ends of a filament coil having straight end portions extending outward from opposite ends of the coil substantially parallel to the axis of the coil, a die member having sides sloping obliquely inward and downward from its upper edges, means for holding the filament on said die with its said end portions extending across the said edges of the die and laterally outward beyond its said sides, a pair of slide members mounted above said die member and each carrying a downwardly extending clamping finger movably mounted in said slide in alignment with one of the said edges of said die member, an angular movable die member pivotally mounted on each of said slide members at one side of the adjacent finger, each of said movable die members extending downward from its pivot and then laterally toward the adjacent finger, means resiliently urging each of said die members about its pivot to hold its end against the adjacent finger, means for moving said slide members downward to first cause said fingers to clamp parts of the end portions of the filament against said first-mentioned die member and, upon further movement, to cause said ends of the movable die members to bend the free end portions of the filament down around the said edges of said first-mentioned die member, and means for then

causing said movable die members to be pivoted under added pressure to press the said filament end portions against the sloping sides of said first-mentioned die member.

- 5 11. The method of manufacturing electric lamp filaments which comprises coiling an intermediate portion of a continuous length of wire into a compact helix with the straight end portions extending outward parallel to the axis of the coil, placing the coil with its said end portions resting against separated supports and projecting beyond the supports, clamping said end portions against said supports, and then bending the said end portions around said supports so that they 10 extend laterally of the coil axis.
12. Apparatus for forming filaments for electric lamps and similar devices comprising means for coiling an intermediate portion of a continuous length of wire into a compact helix with the straight end portions extending outward parallel to the axis of the coil, a die comprising separated support arms, means for gripping the coiled portion of the filament and transferring it from the coiling means to the die, a portion of the said 15 gripping and transferring means being shaped to fit in the space between the die arms to hold the filament with its end portions extending across and beyond the sides of said die arms, finger means adjacent said die arms adapted to clamp said filament end portions against said die arms, movable die means adapted to bend the free extremities of said filament end portions into engagement with the sides of said die arms to shape them, and means for actuating the finger means 20 and movable die means at proper intervals.

- 30 13. In apparatus of the class described for reshaping the ends of a filament coil having straight end portions extending outward from opposite ends of the coil substantially parallel to the axis of the coil, a die member comprising separated support arms, means for holding a filament on said die member with its said end portions extending across said die arms and beyond the sides thereof, finger means adjacent said die arms adapted to clamp said filament end portions against said die arms, movable die means adapted to bend the free extremities of said filament end portions into engagement with the sides of said die arms to shape them, and means 35 for actuating the finger means and movable die means at proper intervals.

FRED B. IDEN.
